UNITED STATES PATENT OFFICE.

JOHN W. VAN BROCKLIN, OF SEATTLE, WASHINGTON, ASSIGNOR OF ONE-SIXTEENTH TO RUSSELL L. DUNN, OF SAN FRANCISCO, CALIFORNIA.

WATER-VALVE.

SPECIFICATION forming part of Letters Patent No. 643,076, dated February 6, 1900.

Application filed November 2, 1898. Serial No. 695,335. (No model.)

To all whom it may concern:

Be it known that I, JOHN W. VAN BROCKLIN, a citizen of the United States, residing at Seattle, county of King, in the State of Washington, have invented a new and useful Water-Valve, of which the following is a specification.

My invention relates to improvements in a water-valve used under pressure; and the object of my improvement is to avoid lifting a heavy weight in opening and closing the valve while under pressure. I attain this object by the mechanism illustrated in the accompanying drawings, in which—

15 Figure 1 is a vertical central section of the valve and surrounding case; Fig. 2, a top view of valve and case, half in section on the line A B of Fig. 1; Fig. 3, a top view of valve.

Similar letters refer to similar parts in the 20 several views.

The case C, in which the valve moves, is connected at E with the water main or pipe. (See Figs. 1 and 2.)

25 F is a hollow cylinder having a cross-bar G, to which is attached the valve-stem H, as shown in Fig. 1.

Fitted to the case C is the gland I, which forms the stuffing-box J, as shown in Fig. 1.

30 L shows the gland I cupped to receive a leather band. (See Fig. 1.) This band is riveted to the gland at the upper edge, the lower edge of the band being beveled toward the valve, thus any water passing the packing in box enters back of the leather band, forcing it 35 against the valve, thus preventing any leakage.

The case C is larger than the valve F, allowing the water to entirely surround the valve, (see Fig. 1,) thus presenting no resistance to the opening or closing of the valve, the valve 40 requiring only power sufficient to overcome the friction in the stuffing-box, the water entering and discharging as shown by the arrows.

The valve-seat M is bored to an angle of 45 about sixty degrees, and the valve, having an angle of about forty-five degrees, can be worked by a cam-lever or other device, with a spring attached to avoid a shock.

What I claim as my invention, and desire 50 to secure by Letters Patent, is—

In combination with the cylindrical valve F and a concentric stuffing-box provided with clamping-screws and an internal groove L for packing, a casing provided with an outlet 55 and valve-seat at its bottom, a lateral inlet, a raised upper part adapted to receive the said stuffing-box and an inwardly-presented annular rib for guiding the said valve, the latter fitting at the bottom into the said seat 60 and being of less diameter than the bore of the said casing in which it works, in order that there may be a space for fluid around said valve to the level of the said stuffing-box, substantially as and for the purpose set 65 forth.

JOHN W. VAN BROCKLIN.
